United States Patent Office

Des. 207,378
Patented Apr. 4, 1967

207,378

EGG SLICER

Monte Levin, Roslyn Heights, N.Y., assignor to Rudi Baer, doing business as Progressus Company, New York, N.Y.

Filed Mar. 2, 1966, Ser. No. 1,245

Term of patent 14 years

(Cl. D89—1)

FIG. 1 is a perspective view of an egg slicer showing my new design with the slicer member in raised position:

FIG. 2 is a similar view with the slicer member in lowered position;

FIG. 3 is a top plan view thereof;

FIG. 4 is a side elevational view thereof;

FIG. 5 is a rear elevational view thereof;

FIG. 6 is a front elevational view thereof;

FIG. 7 is a bottom plan view thereof;

FIG. 8 is a sectional view on line 8-8 of FIG. 3; and

FIG. 9 is a sectional view on line 9-9 of FIG. 3.

I claim:

The ornamental design for an egg slicer, as shown.
